UNITED STATES PATENT OFFICE.

BERNHARD COHNEN, OF GREVENBROICH, GERMANY.

CONTINUOUS ROLLER DRYING-MACHINE.

No. 829,141.

Specification of Letters Patent.

Patented Aug. 21, 1906.

Application filed July 14, 1905. Serial No. 269,587.

To all whom it may concern:

Be it known that I, BERNHARD COHNEN, a subject of the German Emperor, and a resident of Grevenbroich, Germany, have invented 5 certain new and useful Improvements in Continuous Roller Drying-Machines, of which the following is a specification.

This invention relates to drying-machines, and especially to drying-machines for loose cotton and other like textile material. In drying-machines of this kind hitherto used the material was dried without being turned up and loosened in order to allow the drying-air to come thoroughly in contact with the material to be treated.

The object of this invention is the construction of a machine in which the material is conveyed continuously through the drying-chamber and constantly turned up, so as to allow the drying-air circulating in opposite direction to exert a powerful action upon the material.

Another object of this invention is to construct a drying-machine in which the free surface upon which the hot air may exert its action is as large as possible and much larger than in any machine hitherto used.

A further object of the invention is to provide a drying-machine of simple construction in which the working parts are exposed to a minimum of tear and wear and which only necessitates very little motive power.

With these objects and others in view my invention consists in the combination of 5 parts as hereinafter pointed out, and specified in the appended claims.

In the annexed drawings, Figure 1 is a longitudinal vertical section of my improved drying-machine. Fig. 2 is a side elevation of same, showing the driving mechanism, certain parts being omitted to simplify matters. Fig. 3 is a vertical transverse section upon line A B of Fig. 2. Fig. 4 is a similar section, on an enlarged scale, showing the gearing of 5 the rollers. Fig. 5 shows a side elevation of the gearing of two horizontal series of rollers. Figs. 6, 7, and 8 show transverse sections of three alternate forms of rollers.

The improved drying-machine comprises a rectangular casing 1, made of sheet metal and figured iron. In this casing is supported a plurality of superposed more or less horizontal series of rollers 2, the trunnions of which traverse the front and rear walls of the 5 casing and are supported in notches of bars secured to the outside of said casing. In

Fig. 4 are shown the front trunnions 3, projecting through the front wall 4 and resting in the notches of the bars 5. As stated, the said rollers 2 are arranged in superposed horizontal layers a b c d, &c. The latter are arranged like baffle-plates, so as to leave an opening 6 alternately at the right and at the left of the casing, as clearly shown by Fig. 1 of the drawings. The casing 1 is provided at 65 its top with a lateral inlet-opening 7, through which an elevator 8 discharges the material to be treated. At the opposite lower end the casing is provided with an outlet 9, through which the dried material escapes. Upon the 70 bottom of the casing heating-pipes 10 are provided, and air is forced into the apparatus through a flue 11, opening from below into the casing by a blower 12 or other suitable apparatus. The hot air escapes from the 75 casing 1 through a chimney 13, mounted upon the top of the latter. The heating-pipes 10 may be dispensed with when hot air is directly delivered by the blower 12.

All the rollers 2 of one horizontal series are 80 rotated in a determined direction in order to convey the material resting upon them toward the openings 6 of each series —i. e., the rollers of the uppermost series turn clockwise, those of the second series in the opposite direction, those of the third series clockwise, and so on. The driving mechanism comprises a horizontal shaft 14, mounted upon the front wall of the casing and carrying the driving loose and fast pulleys 15 16 and a 85 worm 17, meshing with a worm-wheel 18. Upon the shaft of the latter are keyed two sprocket-wheels 18 and 19, the former of which drives, by means of the chain 20, the driving-wheel 21 of the elevator 8, while the 90 other sprocket-wheel 19 drives, by means of a chain 22, a sprocket-wheel 23, mounted upon a shaft suitably secured to the top of the casing 1. Upon the shaft of the sprocket-wheel 23 is keyed a second sprocket 24, which by 95 means of a chain drives sprocket-wheels 25, 26, 27, and 28, respectively keyed upon the prolonged trunnions of any suitable roller 2 of the first, third, fifth, and seventh horizontal series of rollers, respectively. The 100 rollers thus rotated communicate their rotation to all the other rollers of the same series and to those of the series next below by means of small sprocket-wheels 29, keyed upon the trunnions of all rollers near the bars 5. A 105 chain 30, meshing with the upper side of the sprockets of the series containing the driving

sprocket 25, 26, 27, or 28 and by means of directing-sprockets 31 and 32 transmits motion to the upper side of the sprockets of the next series of rollers, thus reversing the direction of rotation of this series. Plates 33, arranged at a suitable small interval above the sprockets 29, prevent the chain 30 coming out of gear with the said wheels. It will be readily seen that all driving parts are situated at the outside of the drying-chamber, and thus protected against the action of the hot air and moisture. The action of the transporting-rollers 2 on the loose material to be treated is so energetic that their number 15 of revolutions need not exceed one per minute.

The construction of the rollers 2 may vary according to the material to be treated. I have shown several sections in Figs. 6 to 8; 20 but it is understood that these forms are only given by way of example and that I do not limit myself to these special forms, which may be varied without departing from the scope of my invention. In the form shown by Fig. 6 the roller is composed of a plurality (six) of L-shaped bars 31, the rib of which is directed toward the outside, an interval being left between two neighboring bars. The construction shown in Fig. 7 comprises a plurality of similarly-arranged U-shaped bars 32, the wings 33 of which are projecting outwardly. In the form shown by Fig. 8 the roller is simply composed of a series of flat bars 34 without radially-projecting ribs. 25 The rows of rollers instead of being horizontal may also be slightly inclined, so as to facilitate the transport of the material. However, inasmuch as the gearing necessary to bring about this different speeding of the various trains of rollers is well known in mechanics of all kinds, I have not deemed it necessary to illustrate it, as it would vary with the particular use to which the machine was to be put and the character of the material to 30 be treated.

The function of my improved drying-machine is as follows: The blower 12 is started, steam supplied to the heating-pipes 10, and rotation imparted to the rollers 2 and the elevator 8. Then the loose material to be treated is supplied to the elevator 8, which discharges it through the opening 7 on the uppermost layer *a* of rollers. These rollers rotating clockwise convey the material continuously from the left to the right until it falls through the opening 6, arranged between the right end of the roller series *a* and the side wall of the casing, the material being prevented from falling through the intervals left between the rollers of the same series by the ribs of the roller and the narrowness of these intervals. The material is thus conveyed in a continuous manner through the apparatus from the top to the bottom of the latter, effecting a zigzag-like travel. During its whole

travel through the machine the material is most thoroughly acted upon by the hot air rising between the rollers of one series through the material and traveling through the zigzag channels left between the roller layers *a*, *b*, &c. The action of the hot air is most efficient, owing to the particular arrangement described above, and the drying action of the apparatus may be controlled in a very satisfactory manner by controlling the speed of the ventilator, the speed of the elevator, the radiating effect of the steam heating-pipes, and the speed of rotation of the rollers.

Having now fully described my said invention, what I claim, and desire to secure by Letters Patent, is—

1. In a drying-machine of the class described, the combination with a casing, of a plurality of superposed substantially horizontal rows of juxtaposed rollers, so staggered that openings are left at opposite ends of each pair of rows between the last rollers of the row and the abutting wall of the casing, means for rotating the rollers of one series or row in one direction so as to transport the material toward the opening at its end, and means for rotating the rollers of the next series below in an opposite direction, means for continuously feeding the material to be treated to the top row and means for producing a current of hot air in the casing in a direction substantially opposite to that of the travel of the material to be treated.

2. In a drying-machine of the class described, the combination with a casing, of a plurality of superposed substantially horizontal rows of juxtaposed rollers, so staggered that openings are left at opposite ends of each pair of rows between the last rollers of the row and the abutting wall of the casing, means for producing a current of hot air in the casing in a direction substantially opposite to that of the travel of material to be treated, a sprocket-wheel keyed upon the trunnion of a suitable roller of each row and rotated in the same direction by means of a driving-chain, a power-shaft, a sprocket-wheel driving the driving-chain keyed upon the end of the trunnion of each roller and an endless sprocket-chain engaging on the inside of one lap and on the outside of the other sprocket-trains of adjacent rows of rollers, whereby the rollers of the two rows are caused to rotate in opposite directions.

3. In a drying-machine of the class described, the combination with a casing, of a plurality of superposed substantially horizontal rows of juxtaposed rollers, so staggered that openings are left at opposite ends of each pair of rows between the last rollers of the row and the abutting wall of the casing, means for producing a current of hot air in the casing in a direction substantially opposite to that of the travel of material to be treated, a sprocket-wheel keyed upon the

trunnion of a suitable roller of each row and rotated in the same direction by means of a driving-chain, a power-shaft, a sprocket-wheel driving the driving-chain keyed upon 5 the end of the trunnion of each roller and an endless sprocket-chain engaging on the inside of one lap and on the outside of the other sprocket-trains of adjacent rows of rollers, whereby the rollers of the two rows are caused to rotate in opposite directions, and bars preventing the said chains from leaving the upper side of the sprocket-wheels.

In testimony whereof I have hereunto set my hand in presence of two witnesses.

BERNHARD COHNEN.
